Primary Examiner—Gary D. Watson

Assistant Examiner—Susan Bennett Hattan

(74) Attorney, Agent, or Firm—Michael Wallace, Jr.

(57) **CLAIM**

The ornamental design for a closure, as shown and described.

DESCRIPTION

FIG. 1 is a perspective view of the closure of my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken line showings of threads and the interior of the bottom of the closure are for illustrative purposes only and form no part of the claimed design.
